UNITED STATES PATENT OFFICE.

CHARLES J. VAN DEPOELE, OF LYNN, MASSACHUSETTS.

CLOSED SLOTTED CONDUIT.

SPECIFICATION forming part of Letters Patent No. 404,325, dated May 28, 1889.

Application filed March 21, 1889. Serial No. 304,195. (No model.)

To all whom it may concern:

Be it known that I, CHARLES J. VAN DEPOELE, a citizen of the United States, residing at Lynn, in the county of Essex and State of Massachusetts, have invented certain new and useful Improvements in Closed Slotted Conduits, (Case D,) of which the following is a description, reference being had to the accompanying drawings, and to the letters and figures of reference marked thereon.

The present invention relates to improvements in conduits for electric railways of the type in which the supply conductor or conductors are contained within a small sub-surface chamber communicating with the surface by a continuous opening or slot, which slot is kept normally closed by flexible strips of packing, which, being interposed between the conductor-sustaining parts and the exterior casing of the conduit, serves the double purpose of excluding dirt, water, &c., and insulating the conductor-supporting parts from the exterior casing, which may be made of various materials, but is usually of metal. The traveling contact is made with the conductor or conductors by contact devices moved in contact therewith by a thin plate or blade which supports the slot-closing packing during its passage, but which is made quite thin, so that the least possible separation is effected thereby. The elasticity of the packing will cause it to press tightly against the sides of the blade and be almost closed at its front and rear ends. For further protection, however, I supply compressed air to the conductor-containing chamber, the escape of which about the traveling contact will prevent the entrance of foreign matter, and it will be obvious that the supply of air will also result in blowing out of the conduit any accumulations of water that may have entered through leaky or defective portions thereof. The compressed air, however, need only be supplied in wet or very damp weather, since when all the parts are dry the structure and arrangement of the several portions of which the conduit is composed will afford all necessary protection and insulation to the conductors.

The principles of the invention are fully set forth in two prior applications, filed January 5, 1889, and serially numbered, respectively,

ly, 295,506 and 295,507; but this application refers more particularly to certain specific features shown in said prior applications, but not specifically claimed therein, and which will be hereinafter fully described, and referred to in the appended claims.

In the drawings, Figure 1 is a longitudinal vertical section of a conduit embodying my invention, certain of the parts being shown in full. Fig. 2 is a transverse sectional elevation of the conduit shown in Fig. 1. Fig. 3 is a transverse sectional elevation showing a somewhat differently constructed conduit. Figs. 4 and 5 are transverse sectional elevations of slightly differing forms of construction. Figs. 6, 7, and 8 are also transverse sectional elevations of my improved conduit, showing slightly different means for closing the slot. Fig. 9 is a perspective of another form of slot-closing material, and Fig. 9^a is a detail thereof. Fig. 10 is a diagrammatic view of an organization of parts for supplying compressed air to the conduit.

As indicated in the drawings, A represents the exterior casing of the conduit, which is usually composed of continuously-connected metallic sections, substantially as shown, described, and claimed in an application filed by me February 2, 1889, Serial No. 298,432.

The sections of casing A are provided at intervals with supporting-chairs B, upon which and upon the edges of the casing are placed surface or capping plates C C. The capping-plates are removably secured in position and separated to form a continuous slot, D. Within the casing A is placed an insulating-support, E, for the conductor or conductors. The support E is usually in the form of a solid filling of wood soaked or coated with a preservative water-proof compound, and may be formed, as seen in Figs. 1, 2, 3, 4, 5, and 7, of a piece or pieces of timber formed to entirely fill the casing A, and provided with a central groove or grooves, a, for the reception of the conductor or conductors.

As indicated in Figs. 1, 2, and 4, the filling A is provided with a central chamber constructed with a groove on each side for the reception of the positive and negative conductors. The conductors 1 and 2 are shown

as slitted cylindric tubes, the slits being continuous and preferably arranged facing each other.

In Fig. 4 a pair of flat metallic bars, 3 4, are shown; but it will be understood that any desired form of conductor may be employed. In Figs. 5 and 6 single cylindric conductors are indicated, and in Fig. 7 a single flat conductor, 3, is seen.

As described in the said prior application, my improved conduit comprises an exterior casing, an insulating filling or support for the conductor, and means for closing the slit above the conductor-containing groove or chamber with a flexible insulating material, supplying the necessary elasticity and at the same time rendering it highly desirable that some means for lubrication be provided. I find that a combination of leather and rubber possesses many advantages for this purpose, the rubber supplying the necessary elasticity, while the leather will retain and be benefited by the application thereto of a lubricant—for example, a non-drying oil and plumbago. Any material, however, possessing the properties of those above described may be substituted therefor, and will answer the same purpose.

In practice a strip of leather, F, is provided along its rear edge with a strip or cushion of rubber, G, the rubber being attached to the leather by a water-proof cement, or the leather and the rubber may be separately applied; but in either event the rubber is separated or protected from the leather by water-proof material in order to prevent the lubricating material upon the face of the leather strip from soaking into the rubber and destroying it. As indicated, the strip of leather is wider than the rubber and is placed along the top of the filling A. When the conductor-containing groove is wide, supporting-strips a^4 , of hard insulating material or even of metal, may be used to sustain the leather strips F. A similar strip F, also provided with a rubber packing, G, is placed upon each side of the upper portion of the filling A, so that the edges turn upward into a vertical position and lie close against each other. The capping-plates C C are then placed in position, resting directly upon that portion of the leather strip lying upon the filling A. The vertical edges of the strips extend into and desirably occupy the entire space of the slot D between the capping-plates, forming a separable water-proof packing for said slot, although it is not essential that they fill the slot D.

In Fig. 3 the casing A' is in the form of a slotted tube instead of an open trough, as A, and instead of filling the tube A with a core of wood the conductors 1 2 are sustained by bridges H of insulating material, which may be slipped into each tube before the same is placed in position. Upon the upper edges of the tube A' are placed strips h h , which fill the space between the edges of the tube A'

and extend almost even with the tops of the chairs B, upon which the capping-plates are supported. The strips h h are separated to 70 form a continuous slot for the passage of the traveling contact device, and upon their upper surfaces are placed the leather strips F, provided, as before described, with the upturned edges backed by rubber strips or cushions G and extending into and closing the slot D between the capping-plates. The metallic casing A', when used with the bridges or separate supports H for the conductors, should be lined with insulating material H', which 75 may be in the form of a tube of prepared paper or fiber or other material slipped into the tubes A' before the insertion of the conductor-supporting bridges, or it may consist of a coating of durable insulating paint or 80 cement, as preferred. Within this form an open space may exist below the conductors, into which water or other matter entering the conduit by an unforeseen circumstance, will be received, and the conduit is provided at intervals with air-supply inlet-pipes, by which 85 a pressure of air is maintained therein for the purpose of preventing the entrance of foreign matter, especially water; but which will also serve in case of necessity to blow 90 out any accumulations and prevent the short-circuiting of the conductors or other interference with their proper insulation.

The presence of an air-pressure in the conduit above that of the atmosphere would result in the forcible ejection of water therefrom; but to facilitate such action I may place at suitable depressions along the line of the conduit exit-pipes B², communicating with a drain-pipe, B³, or suitable catch-basins, and 100 provided with stop-cocks B⁴, which are opened when it is desirable to clear water out of the conduit, and subsequently closed to prevent the escape of air. The escape-pipes B² may also be carried upward to the surface of the 105 roadway instead of to a drain, B³, and provided with stop-cocks protected by a suitable metallic box, B⁵.

Instead of using the solid rubber cushions G a still greater degree of flexibility may be 110 attained by using one or more tubular elastic cushions, G', as indicated in Figs. 6 and 7. The tubes G' are desirably rubber pipes or hose, which are located in rear of the leather facing F, and being separately connected with the pipes supplying compressed air to the conduit or with the interior of the conduit itself, are kept distended thereby. This will enable me to employ a comparatively thin tube, the elasticity of which would, 115 unaided, be sufficient to hold the facing-strips together with sufficient force to properly close the slot, but which, when kept filled with compressed air, would serve the purpose admirably, and in addition would comprise 120 greater flexibility than the solid cushions G. This would be an advantage where a comparatively thick contact-plow were used, as it 125 would permit wider separation of the slot-

closing packing without injury. The tubular cushions G' might be themselves covered with canvas or similar material or with leather and the strips F be dispensed with.

5 As indicated in Fig. 9, the slot-closing strips F F^3 may be held together by a single tubular cushion, G^2 —that is, a cushion be placed behind only one of said strips. One of the cushions G' may serve this purpose; but I 10 may also use the cushion G^2 , which consists of a continuous slanting spiral spring, g^2 , desirably of non-corrosive resilient metal inclosed within a leather or canvas tube, g^3 . The spring g^2 , being placed slanting, may be 15 compressed or flattened by the passing plow, and will possess sufficient power to distend its covering and keep the slot tightly closed. With this arrangement no rubber is used, and the slot may be freely lubricated without in- 20 jury.

In Fig. 8 is seen a form of pneumatic packing, which comprises leather strips F' doubled and having their edges F^2 turned downward, so that the air-pressure within the conduit 25 will always keep the said edges F^2 tightly pressed together.

As shown in Fig. 6, the wooden filling by which the conductor is supported may, if desired, be formed in a number of pieces fitted 30 into the casing to constitute the conductor-sustaining chamber. As there indicated, the conductor 1 is placed in a groove formed in a strip, a' . The leather strips F are then placed about the upper edges of the conductor. 35 Strips a^2 a^3 are then placed within the casing A, being formed to rest upon the lower portions of the strips F , and press them tightly upon the exterior edges of the conductor. Suitable grooves, a^3 , are formed in the strips 40 a^2 , within which are placed the tubular cushions G' , provided with air-supply connections g . When in position, the cushions G' bear against the upper outer surface of the leather strips F , pressing them tightly together. It 45 will be apparent that the solid cushions G may be substituted for the tubes G' . The capping-plates C C rest upon the upper surfaces of the tubes or cushions in the grooves a^3 . The construction indicated in Fig. 7 re- 50 sembles that in Fig. 5, except that tubular cushions G' , formed with air-inlets g' , are substituted for the solid cushions G , and when this form is used it is desirable to undercut the inner edges of the capping-plates 55 C C, to afford greater protection to the said cushions.

The contact devices employed to collect current from the conductors may be in the form of rubbing blocks or brushes, and when 60 blocks are employed they may be cylindric pieces of carbon, J J' , secured between metallic blocks J^2 . Whatever the nature of the contact devices themselves, they are secured to the lower edge of a thin metallic plate, I, 65 which is insulated and moves between the slot-closing packing. For protection to the plate I, a plow or armor, i , is secured about

the portion thereof exterior to the slot and desirably so arranged as to move in close proximity to the capping-plates, so as to remove any dirt or other obstruction therefrom. 70

The armor i is properly insulated from the conducting plate or blade I, and serves to receive the mechanical connections extending to the vehicle by which the contact-plow as a 75 whole is moved along the conduit.

Where two conductors are used, as indicated in Figs. 1, 2, 3, and 4, a convenient arrangement of contact devices is as indicated in Fig. 1, where two separate plows are shown, 80 one somewhat in advance of the other. As indicated in said Fig. 1, the contact devices J J' extend laterally from the lower edges of the plows, one set entering and moving upon the interior of each of the conductors. 85

In the diagram, Fig. 10, a railway system is indicated, together with a system of supplying compressed air to the conduit. Instead of a continuous system of supply-pipes, it will be found convenient in many instances to 90 supply the air from separate stations each provided with air-compressing apparatus, which may consist of an automatic motor supplied with current from the conductors in the conduit and acting when in circuit to 95 continuously maintain the desired pressure. Four such stations are indicated at K L M N, suitable mechanism therefor comprising a motor, k , and a pressure-blower, k' , each supplying air to insulated inlet-pipes P, located 100 at desired intervals along the conduit Q. The conduit itself will, however, serve in most instances to convey the air from a central supply-station throughout its entire length with sufficient facility to prevent the entrance 105 of water under ordinary circumstances.

Various methods of compressing air and supplying the same to the conduit might be used, and, if desired, the motor or motors might be included in a separate circuit, (indicated in dotted lines in Fig. 10,) and thus entirely under control from the generating-station. This arrangement would be specially advantageous in cases where through accident or neglect the conduit had become filled with 110 water during the night or when not in use. The presence of water would render the conduit inoperative; but with the air-compressing apparatus in a separate circuit the water could be ejected and the conduit thoroughly 115 dried by the circulation of air therethrough, by which means a conduit otherwise useless could be put in operative condition in the shortest possible time.

Having thus fully described my invention, 125 what I claim as new, and desire to secure by Letters Patent, is—

1. A conduit for electric conductors, comprising a slotted exterior casing, a conductor or conductors and supports therefor within 130 the casing, flexible or yielding strips between the conductor-supports and the casing, and an elastic cushion or cushions between the flexible strips and the casing for holding the

- strips normally in close contact to close the slot.
2. A conduit for electric conductors, comprising a slotted exterior casing, a conductor or conductors, and an insulating support or supports therefor within the casing, strips of flexible insulating material between the conductor-supports and the casing, and elastic cushions between the casing and the strips 10 acting to hold said strips normally in close contact.
3. A conduit for electric conductors, comprising a slotted exterior casing, a conductor or conductors and supports therefor within the casing, flexible strips between the conductor-supports and the casing, an elastic cushion or cushions between the flexible strips and the casing for holding the strips normally in close contact to close the slot, and means 15 for supplying compressed air to the interior of the conduit to prevent the entrance of water.
4. A conduit for electric conductors, comprising a slotted exterior casing, a conductor or conductors, and an insulating support or supports therefor within the casing, strips of flexible insulating material between the conductor-supports and the casing, and elastic cushions between the edges of the slot of the 20 casing and the strips for holding said strips normally in close contact and closing the slot.
5. A conduit for electric conductors, comprising a slotted exterior casing, a conductor or conductors and supports therefor within the casing, flexible or yielding strips of lubricated material between the conductor-supports and the casing, and an elastic cushion or cushions for holding the edges of the lubricated strips normally in close contact.
6. A conduit for electric conductors, comprising a slotted exterior casing, a conductor or conductors, and insulating-supports therefor within the casing, continuous strips of flexible material arranged along the upper 25 part of the interior of the casing and having their upper inner surfaces in close contact and supplied with lubricating material, continuous supports for the lubricated strips, and elastic cushions acting against the backs 30 of said strips for holding them normally in close contact to close the slot of the casing.
7. A conduit for electric conductors, comprising a slotted exterior casing, a grooved insulating-filling for said casing, a conductor or conductors in the groove or grooves, flexible or yielding insulating-strips interposed 35 between the filling and extending up into the slot of the casing, and elastic cushions against the backs of the strips in the slot and acting to hold them normally in close contact.
8. A conduit for electric conductors, comprising a slotted exterior casing, a conductor or conductors and supports therefor within the casing, flexible or yielding insulating-strips between the conductor-support and the 40 casing, a hollow elastic cushion or cushions between the upper edges of the strips and the casing, and means for distending the cushion or cushions for holding said strips normally in close contact to close the slot.
9. A conduit for electric conductors, comprising a slotted exterior casing, a conductor or conductors and supports therefor within the casing, flexible or yielding insulating-strips between the conductor-support and the 45 casing, hollow elastic cushions interposed between the upper edges of the strips and the casing for normally holding the said strips in close contact to close the slot, and means for supplying compressed air to the interior of the hollow cushions for increasing their pressure upon the slot-closing strips, as desired.
10. A conduit for electric conductors, comprising a slotted exterior casing, flexible slot-closing strips normally in contact to close the 50 conduit, contact devices engaging a conductor or conductors within the conduit, a thin blade or plate carrying contact devices at its lower edge and extending upwardly through the flexible slot-closing material and 55 formed with upwardly-sloping extremities, whereby the slot is opened in an upward direction, but remains tightly closed about the sides of the plate.
11. The combination, with a closed slotted 60 conduit, of an air compressor or compressors, electric motors for actuating the same, a circuit for supplying current to the motors independent of the conduit, and mains or pipes connecting the compressors and the conduit 65 for supplying compressed air thereto.
12. The combination, with a closed slotted 65 conduit, of means for supplying compressed air thereto, comprising one or more air-compressors, and an inlet pipe or pipes connecting the conduit and compressors, and valved outlets for facilitating the egress of water, when desired, and preventing the escape of 70 air.
- In testimony whereof I hereto affix my signature in presence of two witnesses.
